US00D937550S

(12) **United States Design Patent** (10) **Patent No.:** **US D937,550 S**
Belhacene (45) **Date of Patent:** **** Dec. 7, 2021**

- (54) **SHOE**
- (71) Applicant: **NIKE, Inc.**, Beaverton, OR (US)
- (72) Inventor: **Thomas Belhacene**, Portland, OR (US)
- (73) Assignee: **NIKE, Inc.**, Beaverton, OR (US)
- (**) Term: **15 Years**
- (21) Appl. No.: **29/743,854**
- (22) Filed: **Jul. 24, 2020**
- (51) LOC (13) Cl. **02-04**
- (52) U.S. Cl. **D2/962**
- (58) **Field of Classification Search**
